UNITED STATES PATENT OFFICE

2,189,358

DIODE OSCILLATOR TUBE CONSTRUCTION

Philo T. Farnsworth, Springfield Township, Montgomery County, Pa., assignor, by mesne assignments, to Farnsworth Television & Radio Corporation, Dover, Del., a corporation of Delaware

Application March 22, 1937, Serial No. 132,327

8 Claims. (Cl. 250—174)

My invention relates to electron multiplier tubes, and particularly to an electron multiplier tube wherein the fundamental electrodes comprise a simple anode and cathode. The diode 5 of my invention is an efficient electron multiplier and can be used for linear amplification or as a self-oscillator and generator of alternating currents.

The tube structure herein to be described operates broadly in accordance with the method described and claimed in my prior application, Serial No. 692,585, filed October 7, 1933, since matured into United States Patent No. 2,071,515, patented February 23, 1937. The present application is a continuation in part of my prior application, Serial No. 733,837, filed July 5, 1934, since matured into United States Patent No. 2,071,516, patented February 23, 1937, and, in addition, is a continuation in part of my co-pending application, Serial No. 61,042, filed January 27, 1936, since matured into United States Patent No. 2,137,528, patented November 22, 1938. The latter patent refers to various circuits utilized in combination with the diode multiplier tube herein to be described and claimed, whereas the present application refers solely to the tube structure.

Among the objects of my invention are: To provide an electron multiplier tube having a cathode system wherein electrons emitted from one area thereof will impact an opposite area; to provide an electron multiplier tube having a fundamental diode structure which can be utilized for amplification or oscillation generation; to provide a diode structure capable of self-oscillation when the diode electrodes are properly energized and connected by a resonant circuit; to provide a simple and efficient electrode structure capable of producing electron multiplication of a high order of magnitude; to provide an electron multiplier tube having electrodes capable of creating a Faraday space positioned with respect to a cathode sensitized for secondary emission so that secondary electrons emitted pass through the Faraday space; and to provide a simple, efficient electron multiplier tube that is cheap to manufacture and easy to produce commercially in quantity.

Other objects of my invention will be apparent or will be specifically pointed out in the description forming a part of this specification, but I do not limit myself to the embodiment of the invention herein described, as various forms may be adopted within the scope of the claims.

Referring to the drawing:

Figure 1 is a sectional view, partly schematized, of a diode multiplier embodying my invention.

Figure 2 is a cross-sectional view of the preferred form of invention shown in Figure 1, taken as indicated by the line 2—2.

Figures 3, 4 and 6 are simplified diagrams showing alternative embodiments of my invention.

Figure 5 is a diagram showing a multiplier tube with spherical electrodes.

In my United States Patent No. 2,137,528, I have described a system utilized for production and amplification of alternating currents. That system employs an electron multiplier tube not therein claimed, and is fundamentally a diode.

Oscillation generators operating by means of electron stream control, hitherto known in the art, have all comprised tubes having at least three electrodes. In other words, prior oscillation generators and thermionic amplifiers have, as fundamental structure, first, a hot cathode emitting a copious supply of electrons, when heated; second, a collecting anode to which the emitted electrons travel; and third, a control electrode, so positioned as to regulate the number of electrons reaching the anode, in accordance with a potential imposed thereon. It is well known in the art that such a triode is an amplifier, and, in consequence, if energy be fed back from the output or anode circuit to the control electrode circuit in proper phase, the triode becomes an oscillation generator. Inasmuch as the generation of oscillations by this triode is dependent upon the reaction between the input and output circuits and the transfer of energy therebetween, it is obvious that any diode, to generate self-oscillations, must naturally operate on an entirely different principle. Such a principle was discovered and set forth in my United States Patent No. 2,137,528, and may be re-stated here in simple form, as follows: If an electron be accelerated toward a surface capable of producing secondary electrons upon impact with said surface at a ratio greater than unity, electron multiplication will occur, and if repeated similar impacts are made, seriatim electron multiplication of exceptionally high value may be secured before saturation limits the action. I have found that such repeated impacts may take place in a properly arranged diode structure comprising only a cathode sensitized to produce secondary electrons at the required ratio and an accelerating anode so positioned as to direct the electrons into the proper paths between impacts. It was further found and described in my United States Patent No. 2,137,528, of which the present application is a continuation in part, that such a diode will become an efficient oscillation generator with only the connection of a resonant circuit between anode and cathode, together with a steady source of potential imposed upon the anode with relation to the cathode.

I am well aware of the fact that there are many diodes existing in the prior art, beginning with the electron valve of Fleming and contin-

uing to the present day, either in unchanged form, as in hot-cathode rectifier tubes, well known in the art, or, for example, as photoelectric tubes wherein the basic structure is a photoelectric cathode and an anode positioned to collect electrons emitted from the photoelectric cathode under the influence of light or radiant frequencies closely allied thereto. However, none of these prior-art diodes are capable of oscillation generation. The main distinction between my present invention and prior diodes is in the arrangement and structure of the anode with respect to the sensitized surface of an unheated cathode. While such an arrangement of structure may at first glance seem only a trivial departure from the prior art, nevertheless no one has hitherto succeeded in making any diode structure that will self-oscillate. It therefore is obvious that the arrangement of anode structure with relation to an unheated cathode, as herein described and claimed, represents a distinct advance in the art, inasmuch as a new and totally unexpected result has been obtained, namely, a structure which simply needs a steady difference of potential between the anode and cathode and a regulatory resonant circuit to become a highly efficient oscillation generator of high power.

The tubes illustrated in the drawing will now be referred to in order that the principles underlying the design necessary for the production of self-oscillations in the diode may be more fully understood.

Referring to Figures 1 and 2, a tubular envelope 1 is provided at each end with reentrant stems 2 and 3. At one end, stem 2 supports a hollow apertured anode formed, in this embodiment, of fine refractory wire 4, wound as a spiral on upright supports 5, the wire being welded to the supports at each contact therewith. Surrounding the anode and coaxial therewith is a cylindrical cathode 6, preferably unperforated, and supported by leads 7 from stem 3. Anode lead 8 and cathode lead 9 pass through their respective stems so that outside electrical connection can be made. It is obvious, in this regard, that the anode and cathode may be supported in any convenient manner well known in the art.

The inner surface 10 of the cathode cylinder 6 may either be treated so that secondary electrons will be emitted therefrom at a ratio greater than unity when impacted by electrons traveling at a proper velocity, or the entire cathode may be made of a material which, itself, has such a secondary-emission characteristic, and I deem the two to be full equivalents. For example, cathode 6 may be made of aluminum. Cathode 6 may also be made of a barium nickel alloy, treated during the processing of the tube so that the inner surface 10 is sensitive to electron impact to produce secondary electrons. Or, material having a high secondary emissivity may be evaporated by auxiliary containers within the tube and deposited on the inner surface 10. Barium is a good example of such a material. However, I have found that the maximum sensitivity may be obtained by making cathode 6 of silver, oxidizing it, and condensing caesium thereon until maximum secondary electron sensitivity is obtained. I have found that this sensitivity to electron impact does not occur at the point where maximum photoelectric response is obtained, but actually occurs, both with barium and caesium, at the point where maximum thermionic emission occurs, and this point may be found during the processing of the tube by heating the entire

tube in an oven and checking the thermionic emission which, with such materials of low work function, will occur far below the red temperature. I wish it to be distinctly understood, however, that the tube structure does not require exceptionally high sensitivity to electron impact to be operative, either as an amplifier or oscillation generator, because of the fact that as the output of the tube is based on multiple impacts to produce a large number of secondaries, an extra impact or two will make up for a decrease in sensitivity of the cathode surface 10.

After the cathode surface has been sensitized or otherwise treated, the tube is evacuated to a high degree and sealed off the pump. It may be made operative simply by connecting a tuned circuit 11 between anode and cathode, and supplying the anode with a positive potential from anode source 12 through radio-frequency choke coil 14. The cathode and the negative end of source 12 may be grounded. The tube will then become a self-oscillator and will oscillate in two different modes, depending, to some extent, on the relative diameters of the anode and cathode. For example, the anode may be made relatively small, as, for example approximately one-half the diameter of the cathode, and when axially positioned with the anode potential adjusted so that the time of flight of an electron from one point on the cathode through the anode to an opposite point is equal to the period of the tuned circuit 11, the tube will oscillate on what I term the "time of flight" principle, and one secondary-generating impact will occur per cycle. However, if the anode is increased in diameter and its periphery placed closely adjacent the inner surface of the cathode, and the anode potential increased, then the electrons will be accelerated outwardly through the apertures in the anode and will then immediately be returned to the cathode at a point adjacent the point from which they were emitted, several times per cycle. Thus, in the latter case, the electrons are accelerated into the Faraday space produced by the anode and returned to the same side of the cathode, rather than completely crossing the operating space. This mode of operation I term the "multiple impact per cycle" principle. This latter mode of operation does, of course, produce a higher multiplied current, and for that reason I prefer to utilize it. In either case, however, it will be seen that the anode, when energized, forms a Faraday space in the path of the electrons between impacts, and it will also be seen that the anode is positioned within the cathode so that the electrons are accelerated away from the cathode along perpendiculars erected from the cathode surface. These conditions I find desirable, and they distinguish my present tube from prior diodes not capable of producing oscillations, irrespective of outside connections.

Figures 3, 5 and 6 illustrate, diagrammatically, modifications of the fundamental structure shown in Figures 1 and 2. For example, in Figure 3 each end of the cathode 6 is provided with an inwardly turned flange or bevel 15, thus greatly reducing the open space at the end of the cathode. Inasmuch as my device does not depend in any way upon light for its fundamental operation, such closure of the ends is unimportant from the point of light exclusion, but it does prevent, to a large extent, the escape of electrons from the operating space on to the walls of the envelope. For example, referring to Figure 1, it will be seen by those skilled in the art

that the lines of force of the static field at the ends of the cylinder will tend to allow electrons to escape over the edge of the cathode 6 and impact the envelope wall. Inasmuch as these electrons are moving at a relatively high velocity, heating of the walls may occur adjacent the ends of the cathode to such an extent that, in extremely high-power tubes, puncture of the envelope wall may easily take place, or heat strains may be set up, eventually leading to envelope failure. Inasmuch as the electrons pass over the edge of the cathode relatively close to the cathode, the beveled flange 15 prevents practically all electrons from escaping from the operating space to the envelope wall.

If complete insulation of the envelope is desired, the open ends of the cathode may be closed by means of insulating shields 16 and 17, as shown in Figure 4. Here the shields are mounted on one or other of the electrodes, or both, and serve to position the electrodes, and they form a barrier for the passage of electrons. Inasmuch as any electrons impacting these shields will, in all probability, stick and build up a charge on the inward face of the shields, it is obvious that such a charge will, in itself, tend to divert other electrons away from the shields, thus preventing excessive heating thereof.

Figure 5 shows a modification wherein the cathode is in the form of a sphere, and the anode in the form of an inner apertured sphere concentrically positioned with respect to the cathode. The operation will be the same and, of course, very few electrons can escape from such a structure.

Figure 6 shows a preferred design for a high-power transmitting diode, wherein a major portion of the envelope is a metal cathode 6, in this case being preferably formed of copper, sealed to envelope 1 with the well known copper-to-glass ring seal 18. The inner surface of the copper cathode 6 may be sensitized as described in conjunction with the cathode of Figure 1, and the cathode may be cooled during operation, if desired. There are definite advantages in high-power tubes to be obtained by cooling the cathode, inasmuch as the most efficient secondary emitters are usually materials having a low melting point. Thus an excessive rise in temperature of the cathode might, as can readily be seen, damage the emitting surface.

I claim:

1. An electron discharge device comprising an envelope containing as sole electrodes cooperating to form an electron multiplier and self-oscillator when energized, an unheated hollow cathode defining and substantially enclosing an operating space, the inner surface of said cathode being capable of emitting secondary electrons at a ratio greater than unity upon electron impact therewith, and a hollow anode permeable to electrons positioned within said space and enclosing a portion thereof common to substantially all perpendiculars erected from the adjacent cathode surface.
2. An electron discharge device comprising an envelope containing as sole electrodes cooperating to form an electron multiplier and self-oscillator when energized, an unheated cathode defining and substantially enclosing an operating space, the inner surface of said cathode being capable of emitting secondary electrons at a ratio greater than unity upon electron impact therewith, and electron-permeable means for defining

an equipotential space positioned to be traversed by electrons following substantially all perpendiculars erected from said inner surface.

3. An electron discharge device comprising an envelope containing as sole electrodes cooperating to form an electron multiplier and self-oscillator when energized, an outer unheated cylinder having an inner surface capable of emitting secondary electrons at a ratio greater than unity upon electron impact therewith, and an inner cylinder permeable to the majority of secondary electrons generated, and shielding means of insulating material closing the open ends of said outer cylinder, said cylinders being concentric.

4. An electron discharge device comprising an envelope containing as sole electrodes cooperating to form an electron multiplier and self-oscillator when energized, an outer unheated cylinder having an inner surface capable of emitting secondary electrons at a ratio greater than unity upon electron impact therewith, and an inner cylinder permeable to the majority of secondary electrons generated, the ends of said outer cylinder being directed inwardly to intercept electrons leaving the space enclosed by said outer cylinder, said cylinders being concentric.

5. An electron discharge device comprising an envelope containing as sole electrodes cooperating to form an electron multiplier and self-oscillator when energized, an unheated cathode defining and substantially enclosing an operating space, the inner surface of said cathode being capable of emitting secondary electrons at a ratio greater than unity upon electron impact therewith, and an apertured Faraday cylinder positioned with in said space:

6. An electron discharge device comprising an envelope containing as sole electrodes cooperating to form an electron multiplier and self-oscillator when energized, an unheated cathode defining and substantially enclosing an operating space, the inner surface of said cathode being capable of emitting secondary electrons at a ratio greater than unity upon electron impact therewith, and an apertured Faraday cylinder positioned within said space, the walls of said cylinder being at all points substantially equidistant from adjacent points on said cathode.

7. An electron discharge device comprising an envelope containing as sole electrodes cooperating to form an electron multiplier and self-oscillator when energized, an unheated cathode defining and substantially enclosing an operating space, the inner surface of said cathode being capable of emitting secondary electrons at a ratio greater than unity upon electron impact therewith, and electrode means for producing, when energized, a Faraday space permeable to the secondary electrons emitted from said surface.

8. An electron discharge device comprising an envelope containing as sole electrodes cooperating to form an electron multiplier and self-oscillator when energized, an unheated cathode defining and substantially enclosing an operating space, the inner surface of said cathode being capable of emitting secondary electrons at a ratio greater than unity upon electron impact therewith, and electrode means for producing, when energized, a Faraday space permeable to the secondary electrons emitted along paths perpendicular to said surface.
